UNITED STATES PATENT OFFICE.

HAROLD S. LOOMIS, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

INTERLOCKING APPARATUS FOR THE CONTROL OF RAILWAY-SWITCHES.

1,398,785.

Specification of Letters Patent.

Patented Nov. 29, 1921.

Application filed April 11, 1919. Serial No. 289,237.

To all whom it may concern:

Be it known that I, HAROLD S. LOOMIS, a citizen of the United States, residing at Wilkinsburg, in the county of Allegheny and State of Pennsylvania, have invented certain new and useful Improvements in Interlocking Apparatus for the Control of Railway-Switches, of which the following is a specification.

10 My invention relates to apparatus for the control of railway switches, and particularly to apparatus of the type wherein a switch is controlled by a lever of an interlocking machine. More specifically, the invention relates to the indication means provided in such apparatus for governing the movements of the control lever.

In apparatus of this character, as is well understood, the indication means is provided 20 with two circuits, one of which includes a contact controlled by the switch and closed only when the switch is in normal position, and the other of which includes a contact likewise controlled by the switch and closed 25 only when the switch is in reverse position. The switch is, of course, controlled by an intermediate device (such as a relay in an all-electric system, or electrically controlled valve apparatus in the electropneumatic system), which device is, in turn, controlled by the lever. Now let us assume that the lever has been moved from its normal position to the reverse indicating position, that the intermediate device fails to respond 30 to such movement at the time, and that the lever is returned to the normal position, as would be possible with only the apparatus thus far mentioned. Later on, due to the jarring of a passing train or to some other 35 cause, the intermediate device may make the response which it should have made while the lever was in the reverse indicating position, whereupon the switch will move to its reverse position; but the lever will then 40 be in the normal position, that is, in a position which does not harmonize with the position of the switch. As is well understood, this is a condition which cannot be tolerated, and the possibility of such a condition has 45 heretofore been eliminated by introducing a further instrumentality known as a "quick switch" into the control of the indication means, this quick switch being operated by

the control lever. This quick switch requires that when the lever has once been moved 55 from an original extreme position to the opposite indicating position, the movement of the lever must be continued to the opposite extreme position before it can be returned to its original position. This requirement 60 guarantees that the intermediate device responds to the movement of the lever.

One object of the present invention is the provision of means which may be used as a substitute for the quick switch and which 65 will require response of the intermediate device to the movement of the lever before the lever can be returned to its original position, but which will permit of greater flexibility in the movements of the lever than is 70 possible when the quick-switch is employed.

I will describe several forms of apparatus embodying my invention, and will then point out the novel features thereof in 75 claims.

In the accompanying drawings, Figure 1 is a diagrammatic view showing one form of apparatus embodying my invention. Figs. 2, 3, 4 and 5 are views showing modifications of certain parts of the apparatus 80 shown in Fig. 1, and also embodying my invention.

Similar reference characters refer to similar parts in each of the several views.

Referring first to Fig. 1, the reference 85 character A designates a railway switch, which switch is controlled by a lever L, this lever usually being one of a plurality of similar levers in an interlocking machine. The control of the switch by the lever may 90 be accomplished by any one of a number of different forms of apparatus and this control constitutes no part of my present invention. As here shown, the means between the lever and the switch comprises a switch 95 operating and locking mechanism of any desired type represented by the rectangle C, a polarized relay E for the control of this mechanism, and a pole-changer F actuated by the lever for energizing the relay E in 100 one direction or the other through the medium of control wires, 15, 15^a. When the relay E is energized in normal direction as shown, the mechanism C is actuated to move the switch to its normal position, whereas 105 when the relay is energized in the reverse

direction, the mechanism is actuated to move the switch to its reverse position.

The movements of the lever L are controlled by indication means comprising, in 5 the form shown in Fig. 1, a single segment S¹ attached to the lever and having dogs 10 and 11 which coöperate with a latch 26^a controlled by an electromagnet M¹. The magnet M¹ is provided with circuits which are 10 controlled by contacts B' and D' on the lever L, and also by a relay R, known as the "indication relay." This relay R is in turn controlled by a pole-changer P actuated by the switch A, so that the relay repeats the 15 positions of the switch, the control being such that the relay is energized in normal or reverse direction according as the switch is in normal or reverse position, and is de-energized when the switch is in all intermediate 20 positions.

The movements of the lever L are further controlled by a segment S^L attached to the lever and having dogs 7 and 8 which coöperate with a latch 26 governed by an elec- 25 tromagnet M^L. This latter magnet is provided with circuits which are controlled by lever-operated contacts B² and D², and by a back point of the neutral contact 16 of relay R. The segment S^L and its latch 26 are 30 further controlled in such manner as to constitute a "detector lock," and to this end the magnet M^L is provided with an additional or detector circuit controlled by lever-operated contacts X and Y and by a relay 3 35 which is connected with the track rails adjacent the switch A. Relay 3 constitutes part of a track circuit which also includes the switch rails, the track rails adjacent the switch, and a track battery 2.

40 The lever actuated contacts are arranged to operate as follows: Each contact B is closed when the lever is in the normal indicating position, that is, when the lever is stopped by the engagement of dog 10 with latch 26 while the lever is moving from the 45 reverse to the normal position. Each contact D is closed when the lever is in the reverse indicating position, that is, when the lever is stopped by the engagement of dog 11 with latch 26^a while moving from the normal to the reverse position. Contact X is closed when the lever is moved a short distance away from its normal position, that is, when the lever is stopped by the engagement of dog 7 with latch 26. Contact Y is similarly closed when the lever is moved a short distance away from its reverse position, that is, when the lever is stopped by the engagement of dog 8 with latch 26, while 50 the lever is moving from its reverse position. The reference characters applied to these lever-operated contacts are in accordance with the standard nomenclature adopted by the Railway Signal Association.

55 In order to simplify the drawing, I have

in some instances omitted the source of current and the common return wires. In such instances, the symbol + represents one terminal of a source of current, while the symbol O represents the other terminal. 70

The operation of the apparatus shown in Fig. 1, is as follows:

In this view the lever L is shown in normal position and the other parts of the apparatus are in the positions corresponding to this position of the lever. When it is desired to reverse the railway switch A, the lever L is first moved in clockwise direction until it is arrested by the engagement of dog 7 on segment S^L with latch 26. The lever is then in the normal detecting position. This movement is sufficient to close contact X, whereupon if the track circuit comprising battery 2 and the track relay 3 is unoccupied, magnet M^L becomes energized to raise 80 the latch 26 out of the path of dog 7. The circuit for this magnet is from one terminal of a suitable source of current through contact 4 of track relay 3, wire 5, contact X, wire 6, magnet M^L, to the other terminal of the source of current. The lever L can then be moved in clockwise direction until it is stopped in reverse indicating position by the engagement of dog 11 on segment S¹ with the latch 26^a. During such movement of the 90 lever this latch is elevated by dog 10, but is later drawn back to its latching position by the projection 9 on the under surface of segment S¹. Latch 26, which was elevated to permit dog 7 to pass thereunder, returns to 100 its retracted position as soon as the lever is moved out of the detecting position, because of the opening of contact X; if there is any tendency for this latch 26 to remain in the elevated position, it is positively withdrawn by a similar projection 9 of segment S^L. This latch is engaged by dog 8 at the same time that latch 26^a is engaged by dog 11. The lever is now in reverse indicating position, so that contacts D' and D² are 110 closed. During this movement of the lever, the pole-changer P has reversed the polarity of the current supplied to relay E, so that the switch operating and locking mechanism C is actuated to reverse the switch A. 115 As soon as the switch begins to move, pole-changer P is moved out of the extreme position in which it is shown, so that relay R becomes deenergized and is placed on short circuit; after the movement and locking of the switch A have been accomplished, pole-changer P reaches its reverse extreme position, and so causes relay R to become energized in the reverse direction. During the 120 time that relay R is deenergized, magnet M¹ becomes energized through the following circuit—from one terminal of a suitable source of current, through the back point of contact 16 of relay R, wire 17, contact D², wires 18, 19 and 6, and winding of magnet 125 130

M^L to the other terminal of the source. This causes latch 26 to be moved out the path of dog 8, and this movement of the latch closes contact 20, whereupon a holding circuit for magnet M^L is closed, which circuit is independent of contact 16 of relay R. This holding circuit is from one terminal of the source of current, through contact 20, wire 21, and thence through contact D^2 and magnet M^L 5 as before. It follows, therefore, that magnet M^L remains energized after relay R becomes energized and until contact D^2 is opened. When relay R becomes energized in the reverse direction, the indication magnet M^I becomes energized through a circuit from one terminal of a source of current, through the upper point of contact 16 of relay R, wire 22, contact 27-27^a, wire 23, contact D' , wire 24, and winding of magnet M^I , 10 to the other terminal of the source. The energization of magnet M^I raises latch 26^a out of the path of dog 11, so that the lever is then free to be swung to its full reverse position. The movement of the lever to this 15 position opens contacts D' and D^2 , so that latches 26 and 26^a return to their latching positions, the latch 26 being, of course, on the right-hand side of dog 8, so that the lever is locked in the reverse position.

20 The operation of the apparatus to move the switch A from reverse position to normal position, is similar to the operation just described. The release of the lever in reverse position is obtained by moving the lever far enough to close contact Y. On further movement of the lever to normal indicating position, contacts B' and B^2 become closed, so that when relay R becomes energized in normal direction, both latches 26 25 and 26^a are elevated to permit the lever to be swung to full normal position.

Referring now to Fig. 2, the apparatus shown herein is exactly the same as that shown in Fig. 1, except that two segments S^N and S^R are provided for normal and reverse indication, respectively. The lever L is stopped in reverse indicating position by the dog 11 on segment S^R , and it is stopped in the normal indicating position by dog 10 30 on segment S^N . The circuit for releasing the lever in reverse indicating position is from contact 16 of relay R, through wire 22, contact 27-27^a of relay R, wire 23, contact D' , and wire 24, to latch magnet M^R . The circuit for releasing the lever in normal indicating position is from contact 16 of relay R, through wire 22, contact 27-27^b, wire 23, contact B' , and wire 24^a to magnet M^N . The control of magnet M^I by contacts X 35 and Y, and by contacts B^2 and D^2 , is exactly the same as the control of this magnet in Fig. 1.

It is believed that the operation of the apparatus shown in Fig. 2 will be apparent 40 from the foregoing description taken in

connection with the foregoing explanation of the operation of the apparatus shown in Fig. 1.

Referring now to Fig. 3, the apparatus shown herein is similar to that shown in Fig. 2, the difference being that the detector locking feature is incorporated in segments S^R and S^N , segment S^L being used solely for the purpose of requiring that relay R shall be deenergized before the lever can be moved 45 to full normal or full reverse position. The lever is in this instance locked in the normal position by the coaction of latch 26^a with dog 10^a on segment S^N . In order to release the lever, it is moved to the detecting position, wherein contact X becomes closed. If the track relay 3 is energized, magnet M^N becomes energized to release the lever, so that it then may be moved to reverse indicating position. The circuit for magnet M^N 50 is from the contact 4 of relay 3, through wire 5, contact X, and wires 6 and 28^a, to magnet M^N .

The control of magnet M^L is as follows: When the indication relay R becomes deenergized, magnet M^L is energized through a circuit which passes from the back point of contact 16 of relay R, through wire 21, to the winding of magnet M^L . The closure of contact 20, due to the elevation of latch 26, 55 closes a holding circuit for magnet M^L , which circuit is through contact D^2 , wire 19, and contact 20 to the winding of magnet M^L . The lever is, of course, locked in the full reverse position by dog 11^a on segment S^R , and the release from this position is obtained by a sufficient movement of the lever to close contact Y.

It is believed that the operation of the apparatus shown in Fig. 3 will be understood without further explanation.

Referring now to Fig. 4, I have here shown only two segments S^N and S^R , which segments are employed to perform the same functions as the segments in the preceding views, but in a somewhat different manner. The operation of the apparatus shown in this view, is as follows: The lever L is shown in the normal position and the other parts of the apparatus are in the positions corresponding to this position of the lever. When it is desired to reverse the switch A, the lever is first moved to detecting position, wherein contact X is closed and wherein the lever is arrested by dog 10^a on segment S^N . Magnet M^N then becomes energized to release the lever, the circuit for this magnet being from contact 4 of relay 3, through wire 5, contact X, wire 6, contact 29, wire 30, and wire 30^a, to magnet M^N . Contact 29 is closed only when latch 26 is in the latching position, and, consequently, it will be seen that the lever can be released only when magnet M^N is deenergized. The lever can then be moved to its reverse indicating position 125

wherein it is arrested by dog 11 on segment S^N and also by dog 11^a on segment S^R . As soon as the switch A begins to move, relay R becomes deenergized, whereupon magnet 5 M^N becomes energized through a circuit which passes from the back point of contact 16 of relay R, through wire 31, contact D^3 , and wires 32^a and 30^a to magnet M^N . The elevation of latch 26^a closes contact 20^a, so 10 that after relay R becomes energized, magnet M^N remains energized by virtue of its stick circuit which is from contact D^2 , through wire 33^a, contact 20^a, and wire 34^a to magnet M^N . As soon as relay R becomes 15 energized in reverse direction, magnet M^R becomes energized in the same manner as in the preceding views, so that the lever can then be moved to its full reverse position.

The operation of the apparatus during 20 movement of the switch from reverse position to normal position will be understood without further explanation. It will be noted that in order to release the lever from the reverse position, latch 26^a must be in 25 latching position, as, otherwise, the detector circuit for magnet M^R will be open at contact 29^a.

Referring now to Fig. 5, the apparatus here shown is similar to that shown in Fig. 30 1, and the control of the locking magnet M^L by contacts X and Y and by the track relay 3 is exactly the same as in Fig. 1. The control of the indication magnet M^I is as follows: Operatively connected with the 35 switch A is a contact 35 which connects the positive terminal of a source of current with a wire 36 or with a wire 38 according as the switch is in normal or reverse position. Magnet M^I is provided with a circuit which 40 passes from the positive terminal of this source of current through contact 35, wire 36, wire 37, contact B' , wire 24, and magnet M^I to terminal O of the same source of current. This circuit is, of course, closed 45 only when the switch is in normal position and the lever L is in the normal indicating position. Magnet M^I is provided with another circuit which passes from the positive terminal of the source of current through 50 contact 35, wires 38 and 39, contact D' , wire 24 and magnet M^I to the terminal O of the same source of current. This circuit is, of course, closed only when the switch is in the reverse position and the lever is in the 55 reverse indicating position. The first of these circuits I will term the normal indication circuit and the second I will term the reverse indication circuit.

The indication relay, which in this view is 60 designated by the reference character R^a , is controlled by switch-operated contact 35 and by two lever-operated contacts N^D and R^B . Contact N^D is closed while the lever is in the normal position, or the reverse indicating 65 position, or at any point between these

two positions. Contact R^B is closed while the lever is in the reverse position, or the normal indicating position, or at any point between these two positions. One circuit for relay R^a is from the positive terminal 70 of a source of current through contact 35, wire 36, wire 36^a, contact N^D , wires 40^a and 40, and relay R to the terminal O of the same source of current. The other circuit for this relay includes contact 35, wire 38, 75 wire 38^a, contact R^B and wire 40^b.

The energizing circuit for magnet M^L is from the positive terminal of a source of current through contact 16 of relay R^a , wire 17, contact B^2 or D^2 , wires 19 and 6, and 80 magnet M^L to the terminal O of the same source of current. The holding circuit for this magnet is from the positive terminal of the source of current, through contact 20 operated by latch 26, wires 21 and 17, contact B^2 or D^2 , wire 19, wire 6 and magnet M^L to terminal O of the source of current. 85

The operation of the apparatus shown in Fig. 5, is as follows:

When it is desired to move switch A to the reverse position, lever L is moved to its reverse indicating position in the same manner as in Fig. 1. This reverses pole-changer F, so that the switch operating and locking mechanism C is actuated to reverse the 90 switch. As soon as the switch begins to move, contact 35 moves out of engagement with wire 36 and so causes relay R^a to become deenergized. When this occurs, the energizing circuit for magnet M^L is closed, 95 so that latch 26 is moved upwardly out of the path of dog 8, and this movement of the latch closes contact 20, whereupon the holding circuit for magnet M^L becomes closed. When the switch reaches its reverse position, 100 relay R^a again becomes energized but magnet M^L continues to be energized owing to the fact that the holding circuit for this magnet is independent of contact 16 of the relay. The reverse indication circuit is then 105 closed, so that latch 26^a is moved upwardly out of the path of dog 11 and the movement of the lever can then be completed. The movement of the lever to its full reverse position opens contacts D' and D^2 , so that latches 26 and 26^a return to their latching positions, the former latch being, of course, on the right-hand side of dog 8, so that the lever is locked in the reverse position. 115

The operation of the apparatus to move 120 the switch from the reverse to the normal position will be understood from the foregoing explanation.

Referring now to all of the views, it will be seen that when the lever is moving from 125 normal to reverse position it can be released from the reverse indicating position only in the event that relay R or R^a has become deenergized, that is, only in the event that the switch responds. It will furthermore 130

be seen that if the switch A fails to respond to the movement of the lever to reverse indicating position, the lever cannot be returned to its full normal position. The 5 reason for this is that magnet M^L (in Figs. 1, 2, 3 and 5) or magnet M^R (in Fig. 4) cannot become energized to elevate the latch 26 unless relay R (R^a in Fig. 5) is deenergized. On the other hand, assuming 10 that the switch A makes a partial movement in response to movement of the lever L, and that the switch then becomes blocked by an obstruction so that it cannot make a complete movement to the reverse position. The 15 reverse indication obviously cannot be obtained, but the lever L may be returned to normal indicating position, and if the switch A responds by a movement to full normal position, the normal indication will be received and the lever L may be returned to 20 its full normal position.

The apparatus shown in Fig. 5 has the following advantage which does not apply to the structures shown in Figs. 1 to 4. 25 Assuming that when the parts are in the positions shown in Fig. 5, the reverse indication wire 38 becomes crossed with a wire which is connected with positive battery. Then when the lever is moved to the reverse 30 indicating position, relay R^a will continue to be energized through wire 38, contact R^B and wire 40. This will prevent deenergization of the relay, even though the switch responds to the movement of the lever. 35 Magnet M^L will consequently, not become energized and the lever can, therefore, not be released from its intermediate position. The form of the apparatus shown in Fig. 5 provides complete protection, therefore, 40 against improper or premature indication due to crossed indication wires.

Although I have herein shown and described only five forms of apparatus embodying my invention, it is understood that 45 various changes and modifications may be made therein within the scope of the appended claims without departing from the spirit and scope of my invention.

Having thus described my invention what 50 I claim is:

1. In railway traffic controlling apparatus comprising a railway switch, a lever for the control thereof, electromagnetic means controlled by said switch and energized in one 55 direction or the other according as the switch occupies one position or the other and deenergized when the switch occupies intermediate positions, and means controlled by said electromagnetic means for preventing completion of a movement of the lever until the switch has completed its movement in response to a partial movement of the lever; the combination with the foregoing instrumentalities of apparatus controlled by 60 said electromagnetic means for preventing 65

completion of the movement of the lever unless said electromagnetic means becomes deenergized due to movement of the switch away from its initial position.

2. Railway traffic controlling apparatus 70 of the type comprising a railway switch, a lever for the control thereof, repeating means governed by said switch and having three controlling conditions two corresponding to the two extreme positions of the switch and 75 the third corresponding to intermediate positions of the switch, apparatus controlled by said repeating means for locking said lever after a partial movement thereof and releasing the lever after the switch has made 80 a complete movement in response to such partial movement, characterized by the combination with said lever and said repeating means of apparatus controlled by said repeating means for locking the lever in said 85 partially moved position and for releasing the lever only when the repeating means is in the condition corresponding to intermediate positions of the switch.

3. Railway traffic controlling apparatus 90 of the type comprising a railway switch, a lever for the control thereof, and indicating means controlled by the switch and by the lever for locking the lever after a partial movement of the latter and releasing the lever after the switch has completed its movement in response to such partial movement, characterized by the combination therewith of further apparatus controlled by the switch 95 for locking the lever in such partially moved position and releasing the lever only when the switch occupies an intermediate position.

4. Railway traffic controlling apparatus of 105 the type comprising a railway switch, a lever for the control thereof, and indicating means controlled by the switch, and by the lever for locking the lever after a partial movement of the latter and releasing the lever after the switch has completed its movement in response to such partial movement; characterized by the combination therewith, of further apparatus for locking 110 the lever in such partially moved position, and means controlled by the switch and the lever for releasing said further locking apparatus when the switch occupies an intermediate position and for thereafter holding it released until the lever has been moved 115 beyond said position.

5. Railway traffic controlling apparatus of 120 the type comprising a railway switch, a lever for the control thereof, and indicating means controlled by the switch for locking the lever after a partial movement thereof and releasing the lever after the switch has completed its movement in response to such partial movement; characterized by the combination therewith of a detector latch, an 125 electromagnet for actuating said latch, a 130

segment fixed to said lever and having a dog co-acting with said latch to lock the lever in said partially moved position when said electromagnet is deenergized, an energizing circuit for said electromagnet closed only when said switch is in an intermediate position, and a holding circuit for said electromagnet closed only while the latch is in the actuated position and the lever is in said partially moved position.

6. Railway traffic controlling apparatus of the type comprising a railway switch, a lever for the control thereof, and indicating means controlled by the switch for locking the lever after a partial movement thereof and releasing the lever after the switch has completed its movement in response to such partial movement; characterized by the combination therewith of a separate electrically controlled device for locking said lever in said partially moved position, and a circuit for said device controlled by said switch and closed only when the switch is in an intermediate position.

15 7. Railway traffic controlling apparatus of the type comprising a railway switch, a lever for the control thereof, and indicating means controlled by the switch for locking the lever after a partial movement thereof and releasing the lever after the switch has completed its movement in response to such partial movement; characterized by the combination therewith of repeating means controlled by said switch, a separate electrically controlled device for locking said lever in said partially moved position, an energizing circuit for said device controlled by said repeating means and closed only when such means is in the condition corresponding to intermediate positions of the switch, and a holding circuit for said device closed only when the device is energized and the lever is in said partially moved position.

25 8. Railway traffic controlling apparatus of the type comprising a railway switch having a normal and a reverse position, a lever for the control thereof and having normal and reverse positions also normal indicating and reverse indicating positions; characterized by the combination of two segments fixed to said lever and each having two dogs, a latch for each segment coacting with the dogs thereon to lock the lever in normal and reverse indicating positions respectively, an electromagnet for each latch for actuating the latch to release the lever, a circuit for one electromagnet closed only when the switch is in normal position and the lever is in normal indicating position, a circuit for the other electromagnet closed only when the switch is in reverse position and the lever is in reverse indicating position, an energizing circuit for each electromagnet one or the 35 other of which is closed according as the

lever is in normal or reverse indicating position and the switch is in an intermediate position, and a holding circuit for each electromagnet one or the other of which is closed according as the lever is in normal or reverse indicating position and the corresponding latch is in releasing position.

9. Railway traffic controlling apparatus comprising a railway switch, a lever for the control thereof, indication means controlled by the two for locking the lever after a partial movement thereof and releasing the lever after the switch has completed its movement in response to such partial movement, a relay controlled by the switch and by the lever, and energized when the two harmonize in extreme positions but deenergized when the switch occupies an intermediate position, and further means controlled by said relay for locking the lever in said partially moved position and for releasing the lever only when the relay is deenergized.

10. Railway traffic controlling apparatus comprising a railway switch, a lever for the control thereof, locking means for locking said lever in an intermediate position, and means controlled by the switch for releasing said locking means only when the switch occupies an intermediate position.

15 11. Railway traffic controlling apparatus comprising a railway switch, a lever for the control thereof, locking means for locking said lever in an intermediate position, means controlled by the switch for releasing said locking means only when the switch occupies an intermediate position, and apparatus controlled by said locking means and by said lever for keeping said locking means in releasing position until the lever has been moved beyond said intermediate position.

12. Railway traffic controlling apparatus comprising a railway switch, a lever for the control thereof, locking means for locking said lever in an intermediate position, a relay controlled by said switch and arranged to be energized or deenergized according as the switch occupies an extreme or an intermediate position, and means controlled by said relay for releasing said locking means only when the relay is deenergized.

17 13. Railway traffic controlling apparatus comprising a railway switch, a lever for the control thereof, locking means for locking said lever in an intermediate position, a relay controlled by said switch and arranged to be energized or deenergized according as the switch occupies an extreme position or an intermediate position, means controlled by said relay for releasing said locking means only when the relay is deenergized, and means controlled by said locking means and by said lever for keeping said locking means in the releasing position until the lever has been moved beyond said intermediate position.

14. Railway traffic controlling apparatus comprising a railway switch, a lever for the control thereof, locking means for locking said lever in an intermediate position, a 5 relay controlled by said switch and arranged to be energized or deenergized according as the switch occupies an extreme position or an intermediate position, an energizing circuit for said locking means including a 10 back contact of said relay, and a holding circuit for said locking means including a contact which is closed only when the locking means is in releasing position and a contact which is closed when said lever is in said 15 intermediate position.

15. Railway traffic controlling apparatus comprising a railway switch, a lever for the

control thereof, locking means for locking said lever in an intermediate position, means controlled by the switch for releasing said 20 locking means only when the switch occupies an intermediate position, additional locking means for locking said lever in said intermediate position, and means for releasing said additional locking means only when the 25 switch has made a complete movement in response to the partial movement of said lever to said intermediate position.

In testimony whereof I affix my signature in presence of two witnesses.

HAROLD S. LOOMIS.
